[57] **CLAIM**

The ornamental design for a exterior surface of a sidewall for a juice container, as shown and described.

DESCRIPTION

FIG. 1 is a top, front, right side isometric view of a exterior surface of a sidewall for a juice container showing the new design;

FIG. 2 is a top plan view thereof; and,

FIG. 3 is a front elevational view thereof.

The paritally undisclosed right side and the undisclosed left side and rear are the same as the front seen in FIG. 3. The neck shown at the top in broken lines is for illustrative purposes only and forms no part of the claimed design.
